FILLING CARRIER TRANSFERRING
MECHANISMWallace Hamilton, Hopedale, Mass., assignor to
Draper Corporation, Hopedale, Mass., a corpora-
tion of Maine

Application April 9, 1943, Serial No. 482,419

5 Claims. (Cl. 139—243)

The present invention relates to filling replenishing looms and, as illustrated herein, relates more particularly to means for controlling the operation of mechanism for transferring successive filling carriers to a shuttle during operation of the loom.

In automatic looms of the type referred to above, the filling carriers are transferred from the holder or hopper to the shuttle without interrupting the operation of the loom. The transfer operation is performed as the lay approaches front center and takes place in a very short period of time. Such rapid operation, which is performed suddenly and almost instantaneously, necessarily entails considerable strain and shock, particularly in stopping the transfer mechanism at the end of its transferring movement. It has not been practical to provide a solid stop to limit movement of the transfer mechanism because of the high speed of the parts. Stopping of the transfer mechanism has been effected by the use of a torsion spring which operates also to return the transfer mechanism to its initial position and also operates to rotate the bobbin holding mechanism to present another bobbin or filling carrier into transfer position. A very heavy spring has been necessary in order to stop the mechanism at a predetermined desired point. Such a heavy spring, however, is objectionable since it causes undue wear on the parts.

In accordance with this object, one feature of the invention resides in spring means interposed between the transerrer and a part of the loom to resist movement of the transerrer only during the latter portion of its transferring movement. As illustrated, the stop member comprises a holder fixed to the transerrer arm and carrying a spring which is arranged to engage a stop fixed to a stationary part of the loom. This construction permits a lighter torsion spring to be used to return the transerrer to its initial position and as a result wear on the transerrer parts is substantially reduced.

With the above and other objects and features in view, the invention will now be described with particular reference to the accompanying drawing in which:

Fig. 1 is a view in side elevation, partly in section, showing the transfer mechanism in operated position;

Fig. 2 is a detail view on an enlarged scale of a portion of a transerrer having a resilient adjustable stop applied thereto; and

Fig. 3 is a sectional view taken along the line III—III of Fig. 2.

The loom frame 10 is of usual construction and is provided with a hopper stand 12 on which is mounted a rotatable hopper of which only the butt end disk 14 is shown. The disk 14 is provided with the usual bobbin seats 16 and a ratchet 18 is fixed to the disk 14 in the usual manner. The ratchet is rotated step-by-step to move successive filling carriers 20 into transferring position.

10 The transerrer 22 is of usual construction and is supported for rocking movement on a stud 24 fixed to the hopper stand 12. An arm 26 projects downwardly from the hub 28 of the transerrer 22 and is pivotally connected at its lower end to a latch finger 30, the end 32 of which is arranged upon transfer or replenishment of filling, to be raised into the path of movement of a bunter 34 carried by the lay 36. A feed pawl 38 of usual construction is carried by the transerrer on a pin 40 and operated to rotate the butt end disk 14 when the transerrer 22 is returned to its initial or inoperative position under the influence of the usual torsion spring 42.

When a filling carrier 20 is in transferring position and substantial exhaustion of the filling on a carrier in the shuttle 44 has been indicated by suitable feeling mechanism, the bunter 34 will engage the latch finger 30 as the lay moves into its forward position. Thus the depending arm 26 will be swung rapidly in a clockwise direction and causes the transerrer 22 to be swung rapidly downwardly to move a filling carrier 20 out of a seat 16 in the disk 14 and down into engagement with the empty or substantially empty filling carrier 20, and forcing said last mentioned filling carrier out of the shuttle. As the lay begins its rearward movement, the transerrer begins to move upwardly under the influence of the spring 42. The feed pawl 38 moves with the transerrer and rotates the disk 14 in a direction to move the next filling carrier 20 into transferring position.

The parts described above are of usual construction and operate at the high speeds usual in modern high speed looms. The transferring operation takes place during a very short period of time and without stopping the loom. There is considerable lost motion between the various parts of the transferring mechanism and hence it is difficult to prevent overthrow of the transerrer. Such overthrow is prevented to a substantial extent by the spring 42 which also acts to return the transerrer to its initial position. However, when the parts become worn, the action 55 of the spring 42 is not sufficient to prevent over-

throw and, consequently, the worn parts must be replaced.

Downward movement of the transferer 22 is limited in the present construction by a coiled spring 46 which is secured to the transferer 22 and which engages a plate 48 fixed to the hopper stand 12 by suitable rivets 50. The spring 46 is mounted in a member 52 having a cup-shaped portion 54 in which the spring 46 is secured by a rivet 56. The member 52 is provided with a vertically extending portion 58 which is seated against the side of the transferer 22 and is provided with a threaded opening for receiving a cap screw 60 which in turn passes through an opening in the transferer arm 22. The cap screw 60 is tightened and clamps the member 52 in position on the transferer.

When the transferer 22 approaches the lowermost limit of its transferring movement, the coiled spring 46 will engage the abutment plate 48 and be compressed. The compression of the spring 46 is limited by the cup-shaped portion 54, the lower surface of which will engage the plate 48 to stop the movement of the transferer arm 22. The spring 46, consequently, acts as a resilient cushion and slows down the transferer to such an extent that there is no danger of breakage of parts when the solid cup-shaped portion 52 contacts the step or abutment plate 48. When the lay begins its rearward movement, the tension on the spring 46 is sufficient to initiate the return movement of the transferer arm 22 and the feed pawl 38. As a result, the tension of the spring 42 can be substantially reduced and consequently wear on the feed pawl and transferer parts will be substantially reduced.

Having thus described my invention, what I claim as new and desire to secure by Letters Patent of the United States is:

1. In a filling replenishing loom, a holder for a series of filling carriers, a transferer movable to transfer successive filling carriers from said holder, a supporting member fixed to the transferer, a stationary stop member, and a spiral spring fixed to said supporting member and arranged to engage said stationary stop when the transferer approaches the end of its transferring movements.

2. In a filling replenishing loom, a holder for a series of filling carriers, a transferer mounted for movement to transfer successive filling carriers from said holder, a stationary stop member fixed to the loom, a support fixed to the trans-

ferer and having a spring receiving recess therein, and a coiled spring fixed in said recess and having an end portion projecting below said support and arranged to be compressed by engagement with said stop when the transferer approaches the end of its movement to limit movement of the transferer.

3. In a filling replenishing loom, a holder for a series of filling carriers, a transferer mounted for movement to transfer successive filling carriers from said holder, a stop member fixed to the loom, a support fixed to the transferer and having an open bottomed recess, and a spring riveted to said recess and having an end portion projecting below said recess and arranged to be compressed by engagement with said stop when the transferer approaches the limit of its movement, said spring member being compressed to permit said support to engage said stop positively to limit the transferring movement of the transferer.

4. In a filling replenishing loom, a holder for a series of filling carriers, a transferer mounted for movement to transfer successive filling carriers from said holder, a stop secured to the loom, a support secured in fixed position on said transferer, and a spiral spring having one end portion secured to said holder and projecting below said support a distance sufficient to engage said stop when the transferer approaches the limit of its transferring movement, said spring being compressed sufficiently during the remainder of said transferring movement to permit said stop to engage said support positively to stop the transferer.

5. In a filling replenishing loom, a rotatable holder for a series of filling carriers, a transferer mounted for movement to transfer successive filling carriers from said holder, a stop secured to the loom close to one side of the path of movement of the transferer, a support having a cup-shaped recess mounted on the side of the transferer above said stop, and a spiral spring having its upper end secured to the closed end of said recess and having its other end projecting below said recess a distance sufficient to engage said stop when the transferer approaches the limit of its transferring movement, said spring being compressed and received entirely within said recess to permit said spring support to engage said stop to positively limit the movement of the transferer.

WALLACE HAMILTON.
